UNITED STATES PATENT OFFICE.

JOHN H. CHADWICK, OF PHILADELPHIA, PENNSYLVANIA, ASSIGNOR TO
EDWARD F. MASON AND GEORGE N. SCHOFIELD.

DESIGN FOR A WOVEN FABRIC.

SPECIFICATION forming part of Design No. 23,055, dated February 13, 1894.

Application filed December 1, 1893. Serial No. 492,543. Term of patent 3½ years.

To all whom it may concern:

Be it known that I, JOHN H. CHADWICK, a subject of the Queen of Great Britain, residing at Philadelphia, in the county of Philadelphia and State of Pennsylvania, have invented and produced a certain new and original Design for a Rug, of which the following is a full, clear and exact description, reference being had to the accompanying drawing, forming a part of this specification.

My invention relates to the surface ornamentation of carpet fabrics and is chiefly designed as a pattern for a rug.

The design is illustrated in the accompanying drawing in which A represents the plain ground of the fabric.

The distinguishing features of the design

are the bouquet B of roses, tulips and leaves at the base, extending upward into a center ground formed by a series of scallop-like lines C, and surrounding this is a series of irregular shell-like edges, D. Floral ornamentation such as E may be added to partially surround the whole.

I claim—

The design for a rug or other carpet fabric substantially as shown and set forth.

In testimony whereof I have hereunto affixed my signature this 28th day of November, A. D. 1893.

JOHN H. CHADWICK.

Witnesses:

WILLIAM H. KENNEDY,
WM. J. CURRAN.
